FASTENING-PULLING MACHINE

Fred L. MacKenzie, Beverly, Mass., assignor to
 United Shoe Machinery Corporation, Paterson,
 N. J., a corporation of New Jersey

Application April 29, 1931. Serial No. 533,707

15 Claims. (Cl. 12—16)

This invention relates to machines for pulling fastenings and is herein illustrated as embodied in a machine for pulling staple fastenings from shoes. However, it is to be understood that the 5 invention is not limited to use in connection with machines for pulling staples but is adapted to other uses such as, for example, in connection with machines for pulling upper tacks from shoes.

It is an object of the invention to provide an 10 improved fastening-pulling machine which will be especially adapted to use in pulling temporary fastenings from shoes such as, for example, shoes in which the upper and insole are permanently secured together by cement, and in which staples 15 are employed to secure the upper to the insole in lasted position while the cement is setting. To this end, and as illustrated, the invention provides a fastening-pulling machine comprising an oscillatory tool, gage members positioned beyond 20 opposite ends of a portion of the path of the tool for locating in a direction transverse to said portion of the path a fastening in a shoe presented to the gage members, and a gage member for engaging the side of the shoe for locating the 25 fastening along the path in position to be pulled by the tool. Preferably the tool is in the form of a claw arranged to move inwardly over the margin of the upper throughout the pulling portion of its path, two of the gage members being located 30 to engage a shoe upon opposite sides of a line of fastenings therein firmly to support the shoe against the thrust of the claw during the pulling operation, and a third gage member being positioned outwardly of the claw and adapted to engage 35 the side of the shoe so to guide the shoe that fastenings of the line of fastenings are located successively in the pulling portion of the path of the claw.

The construction above outlined makes it possible 40 readily to present a shoe to the gage members in operative position relatively to the pulling tool which is adapted to engage the cross bars of partially driven staple fastenings and to withdraw them without any likelihood of injury to the 45 shoe. The gage member for engaging the side of a shoe is advantageously located forwardly of the frame of the machine in which position it facilitates the presentation and guiding of the shoe.

Other objects and features of the invention will 50 be pointed out in the claims.

In the drawing,

Fig. 1 illustrates a side view of a portion of a machine embodying one form of the invention;

Fig. 2 illustrates details of the fastening-pulling 55 claw and gage members; and

Fig. 3 is a perspective view of portions of the gage members and claw shown in operative relation to work presented thereto.

The fastening-pulling machine shown in the 60 illustrated embodiment of the invention comprises an oscillatory fastening-pulling tool in the form of a claw 10 having at its end portion a plurality of narrow pointed teeth 12 (Figs. 1 and 3) each of which is adapted for insertion beneath the cross bar of a fastening such as one of the staples 14 65 driven through the upper 16 and anchored in the insole 18 of a lasted shoe 20. The claw 10 is carried at the outer end of a lever 22 mounted for oscillation relatively to the frame 24 of the machine. The central portion of the lever 22 is 70 secured to a rock shaft 26 mounted in the frame and having a crank arm 28 which carries a crank pin 30 upon which the lever is held by a disk 32 and a stud 34. The inner end of the lever 22 is 75 operatively connected to a drive shaft 36 by means of a crank 38 secured to the shaft and having a crank pin 40 upon which the end of the lever 22 is mounted and is secured thereto by a washer 42 and a nut 44. The drive shaft 36, through the crank 38, imparts to the lever 22 an 80 oscillatory movement which is modified by the rocking of the shaft 26 with the result that the claw 10 at the outer end of the lever 22 is given a movement in a closed path somewhat elliptical 85 in shape as shown by dotted lines indicated by reference character 46 in Fig. 2. Adjustment of the shape and size of the path of movement of the claw is provided for by pin-and-slot connections 48 and 49 by which the claw can be adjusted on the lever 22 in two directions. 90

In order to position a shoe with the fastenings 95 therein located in operative relation to the path of the claw 10 and for guiding the shoe past the claw, the machine is provided with a plurality of gage members 50, 52 and 54. These gage members are located in proximity to the claw 10 and are carried by an extension or arm 56 on the body portion of the frame 24.

The gage member 50 extends downwardly from the extension 56 and has a work-engaging portion 58 extending laterally across the path of movement of the claw but spaced rearwardly thereof. The gage member 50 constitutes a work support arranged to engage the bottom of a shoe, such as shoe 20, on one side of a line of fastenings therein. The gage member 50 is secured to the extension 56 by screws 60 extending through elongated slots 62 in the member 50 and into the extension 56. This construction provides for vertical adjustment of the gage for locating the 105 110

inner portion of the shoe in a direction transverse to or heightwise of the path of movement of the claw.

The gage member 52 is mounted in a slot 64 in a lateral projection 66 in the extension 56 and has a downwardly and inwardly curved portion 67. The gage member 52 can be adjusted vertically and can be locked in adjusted position by means of a screw 68 extending through an elongated slot 70 in the gage and into the projection 66. The gage 52 acts as a guard to prevent injury to the work or to the operator by the claw 10, and in the operation of the machine the inwardly curved end 67 of the gage makes contact with the inturned marginal portion of the upper to provide a work support which, in connection with the gage member 50 on the other side of the line of staples, limits upward movement of a shoe presented to the gages and thereby locates staples to be pulled at such position transverse to or heightwise of the path of movement of the claw 10 that the cross bars of the staples, such as partially driven staples 14, are located slightly above the lowermost point of the path of the claw 10.

The gage member 54 comprises a shank 72 secured to the outer portion of the extension 56 by a screw 74 and by a screw 76 extending through a curved slot 78 in the gage member. The lower end of the gage member 54 is provided with a vertically extending, slightly curved surface 80 adapted to engage the side portion of a shoe presented to the machine and to guide the shoe in such manner as to present a line of fastenings 14 along the margin thereof substantially at right angles to the path of movement of the claw. Adjustment of the gage member 54 outwardly or inwardly of the claw is attained by loosening the screws 74 and 78 and rocking the lower end of the gage about the screw 74 as a pivot.

The gage members 50, 52 and 54 above described provide means for locating and guiding the fastenings in predetermined positions relatively to the path of the claw 10. As illustrated in Figs. 2 and 3, a portion of the shoe 20 has an upper 16 the marginal portion of which is lasted over the insole 18 and secured thereto by partially driven clinched staples 14 which, in practice and as shown, are located in a line along the margin of the upper at a substantially constant distance from the side of the shoe. It is to be noted that the side of the shoe 20 is shown in engagement with the face 80 of the gage member 54 which is adjusted longitudinally of the claw in position to locate the line of staples substantially along the lowermost portion of the path of the claw which is shown about to engage a staple beneath the cross bar thereof. The gage member 52 engages the marginal portion of the upper upon one side of the line of staples and the gage 50 engages the insole 18 on the other side of the line of the staples, thus firmly to support the shoe in operative position heightwise of the pulling portion of the path of the claw 10 with the cross bars of the staples located slightly above the lowermost portion of the path in position to be engaged by one of the teeth 12 when the staples are brought into the path of the claw. The gage member 52 is operative to prevent rotation of the shoe about the gage member 50 under the thrust of the claw in pulling a staple.

In the operation of the machine, a shoe, such as shoe 20, is presented bottom-up to the gage members 50 and 52 which engage the bottom of

the shoe on opposite sides of the line of staples 14 and locate the shoe heightwise of the path of the pulling claw 10 with the cross bars of the staples extending slightly above the lowermost portion of the path of the claw. The shoe is held outwardly of the claw against the gage member 54 and is then advanced substantially at right angles to the path of movement of the claw so guided by the gage member 54 that the staples are directed into the pulling portion of the path thereof. The claw, which is oscillated, operates to pull the staples as the shoe is advanced. Since the claw in pulling a staple operates from the outer portion of the shoe inwardly over the upper and since the gage members prevent movement of the shoe into the path of the claw, likelihood of injuring the shoe is avoided. It is to be noted that in its effective or pulling position of its path the claw follows a path which is substantially a continuation of the curve of the clinched portion of the staple with the result that staples can be pulled with a minimum of resistance, thus avoiding any likelihood of injuring the upper of the shoe as the clinched portion of the staple is withdrawn therefrom.

Having described my invention, what I claim as new and desire to secure by Letters Patent of the United States is:—

1. A fastening-pulling machine comprising an oscillatory tool, gage members located beyond opposite ends of a portion of the path of the tool for locating in a direction extending transverse to the said portion of the path a fastening in a shoe presented to the gage members, and a gage member for engaging a side of the shoe for locating the fastening along said portion of the path of the tool in position to be pulled by the tool.

2. A fastening-pulling machine comprising an oscillatory tool movable in a definite path, gage members located in alignment with said path beyond opposite ends of a portion thereof for locating a shoe in predetermined position transversely of the path, and a gage member for engaging a side portion of the shoe to guide fastenings located along the bottom of the shoe toward said portion of the path.

3. A fastening-pulling machine comprising an oscillatory tool movable in a definite path, gage members located beyond opposite ends of a portion of the path of the tool for locating in a direction extending transverse to the said portion of the path a fastening in a shoe presented to the gage members, a gage member for engaging a side of the shoe for locating the fastening along said portion of the path of the tool in position to be pulled by the tool, and means for permitting variation of the position of one of the gage members relatively to the path of the tool.

4. A fastening-pulling machine comprising an oscillatory tool movable in an orbital path, gage members located along the path beyond opposite ends of the lowermost portion of the path for locating heightwise of the path a shoe presented to the gage members, and a gage member for engaging a side portion of the shoe to guide a line of fastenings in the shoe toward said portion of the path of the tool.

5. A machine for pulling fastenings comprising a fastening-pulling claw movable in a closed path, shoe-engaging members located in alignment with the path of the claw and operative to engage a shoe upon opposite sides of a line of fastenings therein, and a gage member for engaging a side portion of the shoe successively to

locate fastenings in the line of fastenings along the path in position to be pulled by the claw.

6. A fastening-pulling machine comprising a frame, gage members carried by the frame for locating a shoe with a line of partially driven fastenings therein in predetermined position heightwise and laterally of the frame, an oscillatory fastening-pulling tool, and means for moving the tool outwardly of the frame across the line of fastenings downwardly into proximity to a fastening and inwardly and upwardly to engage and pull the fastening.

7. A staple fastening-pulling machine comprising a frame, a tool movable in a definite path outwardly of the frame and downwardly preparatory to engaging a partially driven staple fastening in a shoe presented to the tool and inwardly and upwardly to engage and pull such fastening, means located along the path of the tool for positioning the shoe with the fastenings therein located in predetermined position heightwise of the tool in its movement along the pulling portion of its path, and a shoe-engaging member disposed outwardly of the frame beyond the tool for guiding the fastening into the pulling portion of the path of the tool.

8. A staple fastening-pulling machine comprising an oscillatory tool movable in a curved path in the effective portion of which the tool is adapted to engage and pull a staple fastening in a shoe presented to the tool, a member located along the path upon one side of said portion of the path adapted to engage the upper of a shoe, a member located along the path upon the other side of said portion of the path adapted to engage the bottom of the shoe, said members being co-operable with each other to locate a shoe with a line of staple fastenings therein in predetermined position transversely of the path of the tool, and a gage member for guiding the shoe past the tool with the line of fastenings directed toward the effective portion of the path of the tool.

9. A staple fastening pulling machine comprising an oscillatory tool movable in a definite path, gage members located along a portion of the path for positioning a shoe with the cross bars of a line of staple fastenings therein located in predetermined position heightwise of a portion of the path, and a gage for guiding the shoe past a tool with the line of staple fastenings directed toward the said portion of the path of the tool.

10. A fastening-pulling machine comprising an oscillatory claw movable across a line of fastenings in a shoe presented to the machine, a member positioned outwardly of the main body portion of the machine and of the claw and adapted to engage the side of a shoe to guide the shoe past the claw, a gage member positioned inwardly of the claw for engaging the shoe upper upon one side of the line of fastenings, and a

gage member for engaging the shoe upon the other side of the line of fastenings.

11. A fastening-pulling machine comprising an oscillatory tool, and gage members for locating a shoe presented to the members with a line of fastenings in the shoe in operative position relatively to the tool, one of said gage members being positioned beyond the tool outwardly of the main body portion of the machine for engaging the side of a shoe to guide the shoe past the tool.

12. A fastening-pulling machine comprising an oscillatory claw, a member positioned between the claw and the main body portion of the machine for engaging the bottom of a shoe on one side of a line of fastenings therein, a guard member positioned on the other side of the claw for engaging the bottom of the shoe on the opposite side of the line of fastenings, and a gage positioned adjacent to the guard member for engaging the side of the shoe to guide the line of fastenings into the path of the claw at a predetermined distance laterally of the gage.

13. A fastening-pulling machine comprising a frame having a body portion and an arm, an oscillatory tool mounted in the frame and movable in a closed path, a gage member mounted upon the arm and extending in proximity to the path of the tool for locating in operative position relatively to a predetermined portion of the path of the tool a shoe having fastenings therein, and a gage member mounted upon the arm on the side of the tool away from the body portion of the frame for engaging the side of the shoe to guide the shoe past the tool with the fastenings directed toward said portion of the path of the tool.

14. A fastening-pulling machine comprising a frame, an oscillatory pulling tool mounted in the frame and movable in a curved path, a gage member for locating in predetermined position heightwise of the path of the tool fastenings in the bottom of a shoe presented to the gage member, and a second gage member located outwardly of the frame beyond the tool for guiding the shoe past the tool with the fastenings in alignment with a predetermined portion of the path of the tool.

15. A fastening-pulling machine comprising a frame, an oscillatory pulling tool mounted in the frame and movable in a definite path, a gage member for locating in predetermined position heightwise of the path of the tool fastenings in the bottom of a shoe presented to the gage member, a second gage member located outwardly of the frame beyond the tool for guiding the shoe past the tool with the fastenings in alignment with a predetermined portion of the path of the tool, and means for permitting variation of the position of the gage members relatively to the path of the tool.

FRED L. MACKENZIE.
